(57) **CLAIM**

The ornamental design for a holster device, as shown and described.

DESCRIPTION

FIG. 1 is a front top perspective view showing the right-handed version of the holster device showing the new design;

FIG. 2 is a left bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front top perspective view showing the left-handed version of the holster device;

FIG. 10 is a left bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front top perspective view showing the right-handed version of a second embodiment of the design;

FIG. 18 is a left bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a front top perspective view showing the left-handed version of the second embodiment of the holster device;

FIG. 26 is a left bottom perspective view thereof;

FIG. 27 is a front elevation view thereof;

FIG. 28 is a rear elevation view thereof;

FIG. 29 is a left side elevation view thereof;

(Continued)

FIG. 30 is a right side elevation view thereof;
FIG. 31 is a top plan view thereof; and,
FIG. 32 is a bottom plan view thereof.
In FIGS. 1-32, broken lines show portions of the holster
device which form no part of the claimed design.
